CLAIM

The ornamental design for a smart hub for vehicles, as shown and described.

DESCRIPTION

FIG. 1 is a front, right side perspective view of a smart hub for vehicles showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front, right side perspective view with an extended display thereof;
FIG. 9 is a front view with an extended display thereof;
FIG. 10 is a rear view with an extended display thereof;
FIG. 11 is a left side view with an extended display thereof;
FIG. 12 is a right side view with an extended display thereof;
FIG. 13 is a top view with an extended display thereof; and,
FIG. 14 is a bottom view with an extended display.
The broken lines indicate portions of the article that form no part of the claimed design.
